CAN OR SIMILAR ARTICLE

Jack R. Mell, Grand Rapids, Mich., assignor to The Climalene Company, Canton, Ohio, a corporation of Ohio

Filed Apr. 18, 1963, Ser. No. 74,505

Term of patent 14 years

(Cl. D58—17)

FIG. 1 is a front elevation of a can or similar article showing my new design;

FIG. 2 is a side elevation thereof;

FIG. 3 is a top plan view thereof; and

FIG. 4 is a horizontal sectional view looking in the direction of the arrows 4—4 in FIG. 2.

The rear elevation view of the can or similar article is substantially identical to the front elevation of FIG. 1.

The characteristic features of my design reside in a convexly curved side wall, round in cross-section, with varying increasing and then decreasing diameters from a flat bottom wall to a flat top having a depressed snap-in cap, and there being opposite deep depressions con-

cave in vertical section and convex in horizontal section in the upper half of the side wall as shown.

I claim:

The ornamental design for a can or similar article, substantially as shown and described.
